UNITED STATES PATENT OFFICE

2,441,837

AUTOMATIC WIRE-CUTTING MACHINE

Irving S. Ness and Edward Motekewecz,
Baldwin, N. Y.

Application October 26, 1945, Serial No. 624,658

2 Claims. (Cl. 140—145)

1

The instant invention relates to wire-cutting machines and more particularly to such a machine which automatically cuts wire from a reel into predetermined uniform lengths.

One of the primary objects of the invention is the construction of an apparatus of the character indicated which will automatically unreel, measure and cut a wire rope into pieces of predetermined uniform length.

Still a further aim is the formation of a machine of the type above specified in which the cutting of the wire is electrically controlled and in which the wire being cut serves as the conductor of electric current for controlling the cutting operation.

Yet another purpose is the manufacture of an apparatus of the character set out above which will be efficient in use, formed of comparatively few parts and capable of assembly and operation at relatively low cost.

The above and other aims and objects will be apparent from the detailed description herein-after appearing when taken in conjunction with the appended drawings forming a part hereof to which attention is now directed and in which

Figure 1 is a plan view of the novel wire cutting machine;

Figure 2 is a side elevational view, partly in section, of the machine of Figure 1;

Figure 3 is a sectional view taken on line 3—3 of Figure 1;

Figure 4 is a sectional view taken on line 4—4 of Figure 1;

Figure 5 is a sectional view taken on line 5—5 of Figure 2; and

Figure 6 is a detailed sectional view of a longitudinally apertured guide member.

Referring now to the drawings by reference characters and in which like characters designate like parts in the several views, the letter B indicates the base of the machine which carries a motor M, a solenoid-operated cutter S and a cutting control and disposal unit U. The motor M has a drive shaft 10 provided with a worm 11 for rotating driven shaft 12 which, in turn, has a wire feeding wheel 13 and sprocket 14 keyed thereto. Shaft 10 is supported in spaced bearings 15, 15a and the feeding wheel 13 and sprocket 14 are in spaced relation on said shaft—see Figs. 1 and 3. The periphery of feed wheel 13 is grooved and is equipped with a fibre V-belt 16, while cooperating with said wheel is an idler wheel 17 rotatable on fixed shaft 18 mounted on a supporting standard 19 attached to base B.

2

Idler 17 is preferably formed of rubber or other insulating material.

Reference character W designates the wire which is unreeled from a reel or the like (not shown) to the left in Figs. 1 and 2 by means of feed wheel 13 and its cooperating idler 17, the wire being gripped by fibre V-belt 16 and the rubber material of said idler. Means are provided for guiding the wire W comprising aligned tubes 19 and 20 on each side of solenoid-operated cutter S. Tube 19 has an apertured guide member 19a—see Fig. 6. Tube 20 is preferably supported intermediate its length by an upright supporting member 21 positioned on base B, the latter carrying the unit U comprising wire disposal fibre roller 22 on the end opposite to that on which feed wheel 13 is positioned. The roller 22 is keyed to a shaft 23 mounted on spaced brackets 24, said roller being intermediate said brackets 20 and said shaft having a sprocket 25 similar to sprocket 14 keyed thereto. A sprocket chain 26 connects said sprockets. An idler wheel 27, preferably of brass or the like, cooperates with fibre wheel or roller 22 in a manner to be described 25 more in detail hereinafter. Spaced brackets 24 are adjustable lengthwise of base B, either to the right or to the left as viewed in Figs. 1 and 2, for a purpose which will shortly be apparent.

Turning now to Fig. 5, there is shown a solenoid-operated cutting member comprising a solenoid 28, having a movable core 28a for actuating a cutting member 29 carried by a movable plate 30 guided by posts 31 against tension of coil springs 32 surrounding said posts. The reference numeral 33 designates a die holder for cooperation with said cutting member. Brass idler 27 is rotatably mounted on a stub shaft 27a carried by a bracket 27b. An angle iron 27c is rigidly held on stub shaft 27a and supports a spring 40 pressed electrical contact pin 27d in contact with idler 27.

The operation of the apparatus just described is as follows:

Current is fed to the wire W prior to reaching feed wheel 13 by a contact member 35 or the like. Insulated wheel 13 and its rubber idler 17 are actuated by the motor M and feed wire W through solenoid-operated cutter S to fibre disposal roller 22 and brass idler 27. The latter is electrically connected to the solenoid 28 of cutter unit S by a current conductor 36. When the forward end of the wire reaches idler 27 the circuit is completed and the solenoid-operated cutting member 29 severs the wire thus breaking the circuit. The severed wire is disposed of by the roller 22 which

is rotated by sprocket chain 26. It will be particularly noted that brass idler 27 has a dual function, namely as a contact member to complete the circuit through the wire and in co-operation with roller 22 to aid in the disposal of a cut length of wire. By longitudinally adjusting the unit U relative to the base B the length of each severed piece of wire may be predetermined. Once the unit U is locked in any adjusted position all severed pieces of wire will be of uniform length.

From the above it will be apparent that there has been produced a wire cutting machine well adapted for its intended purpose and commensurate with the objects and purposes of the invention. While the invention has been described in detail it will be apparent to those skilled in the art that various changes may be made in the specific embodiment shown and described. It is contemplated to cover all such and to be limited in this respect only as may be necessary by the scope of the claims hereto appended.

What we claim and desire to secure by Letters Patent is:

1. A machine for cutting wire or the like into pieces of predetermined uniform length comprising means for unreeling wire and feeding same into the machine, a solenoid-operated cutter for severing the wire, means supplying electric current to said wire, means for disposing of the cut pieces of wire, said wire disposal means including a rotatable conductor member, a spring-pressed pin contacting said member and conducting current thereto, said pin being electrically connected to the solenoid of said cutter to operate the latter

when said member is contacted by the current-carrying wire.

2. A machine for cutting wire or the like into pieces of predetermined uniform length comprising a power driven wheel for feeding wire from a reel into the machine, a roller driven from the feed wheel for disposing of the cut pieces of wire, a solenoid-operated cutter disposed between the feed wheel and wire disposal roller, means supplying current to the wire, and an idler roller cooperating with the disposal roller in circuit with said solenoid and operating to complete the circuit through the solenoid upon engagement thereof with the leading end of the wire being fed.

IRVING S. NESS.

EDWARD MOTEKEWECZ.
